(57) **CLAIM**

The ornamental design for a T-stand speaker mounting accessory, as shown and described.

DESCRIPTION

FIG. 1 is a top, rear, left side perspective view of a T-stand speaker mounting accessory showing my new design;

FIG. 2 is a front elevation view thereof;

FIG. 3 is a rear elevation view thereof;

FIG. 4 is a right side elevation view thereof, the left side

elevation view being a mirror image;

FIG. 5 is a top plan view thereof; and,

FIG. 6 is a bottom plan view thereof.

The broken lines environment in FIG. 1 forms no part of the claimed design.
